GRAIN DOOR

Bowen B. Morse, Manitowoc, Wis.

Application January 18, 1934, Serial No. 707,079

6 Claims. (Cl. 20—23)

This invention appertains to closures, and more particularly to a novel door closure for effecting a seal in the openings of grain cars and bins, or wherever a tight closure is desired.

5 As is well known, considerable difficulty is experienced with the sealing of the door openings of grain cars. Usually, special panels, or boards, are nailed to the inner face of the door frame across the door opening, as many panels, or 10 boards, being used as required according to the height of the grain in the car.

Obviously, the continual nailing and the constant withdrawing of the nails soon ruin the panels and door frames, and the panels are often 15 mislaid and lost. Consequently, the use of the panels, or boards, is an expensive item. Likewise, there is a certain hazard in the placing and the removing of the boards, or panels, and also considerable time is required.

20 Various attempts have been made to eliminate the use of the panels, or boards, and certain structures have been proposed. None of these structures, to my knowledge, have been successful, possibly due to the complicated features 25 thereof, or the difficulty of operation when the grain is packed up against the same.

It is, therefore, one of the primary objects of my invention to provide an improved grain door which can be continually used without damage 30 to itself or the car, and which is permanently associated with the car, whereby loss is prevented.

Another salient object of my invention is to provide a door which can be quickly and conveniently operated without danger on the part of 35 the operator, and which will effect a tight closure with the door frame, precluding loss of the grain or other material.

A further important object of my invention is to provide an auxiliary door for grain cars, which 40 can be associated with conventional cars now in use without structural changes thereto, and which will permit the convenient use of the ordinary outer sliding car door, the auxiliary grain door being entirely out of the way of the outer door 45 when the same is either in its operative or inoperative position.

A further object of my invention is the provision of a grain door for railroad cars slidably mounted on a guide-track in a novel manner, whereby the 50 grain door can be readily and quickly moved into or out of the door opening, and swung to a closed position in tight contact with the door frame for preventing loss of the grain.

A further object of my invention is the provision of means for mounting the grain door in a

novel manner on the roller brackets of the guide-track, whereby the grain door can not only be slid into and out of the door opening, but can be moved toward and away from the door frame to effect the positioning of the door in the car and in tight contact with the door frame, said connection permitting the vertical raising of the door within certain limits to assure tight engagement of the door with the floor of the car, and to prevent escapement of the grain below the door when 10 desired.

A further object of my invention is the provision of a grain-proof slide plate carried by the door adjacent to the lower end of the door, whereby release of the grain in back of the door can be 15 accomplished to facilitate the opening of the door when desired.

A still further object of my invention is to provide an improved grain door of the above character, which will be durable and efficient in use, 20 one that will be simple and easy to manufacture, and one which can be placed upon the market and incorporated with a grain car at a comparatively low cost.

With these and other objects in view, the invention consists in the novel construction, arrangement, and formation of parts, as will be hereinafter more specifically described, claimed, and illustrated in the accompanying drawings, in which:—

Figure 1 is a fragmentary side elevation of a railroad car showing my improved grain door applied thereto, the door being shown in its open position, with parts thereof broken away and in section to illustrate structural details.

Figure 2 is a fragmentary, horizontal section through the car, taken substantially on the line 2—2 of Figure 1, illustrating my improved grain door applied thereto, the door being shown in its open position in full lines, and in its closed position in dotted lines.

Figure 3 is an enlarged fragmentary, vertical section through the car, taken substantially on line 3—3 of Figure 1, with my grain door applied thereto, the door being shown in its open position.

Figure 4 is a view similar to Figure 3, taken substantially on the line 4—4 of Figure 1, showing the door in its closed position.

Figure 5 is a fragmentary, vertical section through my improved grain door, taken substantially on the line 5—5 of Figure 1, illustrating the slide plate carried thereby.

Referring to the drawings in detail, wherein similar reference characters designate corresponding parts throughout the several views, the letter 55

R generally indicates a railroad grain car, and A, my improved grain door therefor.

The railroad car R is of the usual, or conventional, construction and includes the side wall 10 having the door opening 11 therein. This opening 11 can be provided with the conventional or any preferred type of door frame. The door opening 11 is normally closed by the usual sliding outer door 12. The upper end of the outer door 12 carries the roller brackets, or castings, 13, and these brackets are slidably mounted on the longitudinally extending track 14 mounted above the door opening.

This door 12 is ordinarily employed when the car is used for transporting ordinary freight, and for effecting a complete closure for the door opening when grain is being carried to prevent unauthorized persons from gaining access to the interior of the car.

20 My improved grain door A can be constructed from any preferred number of panels, or boards, 15 ordinarily employed for preventing loss of the grain, and these panels, or boards 15 can be rigidly secured together in any preferred manner, such as by the use of metal strips, or the like, 16.

25 The door A is of a greater length than the width of the door opening and is adapted to fit inside of the car against the door frame when the door is in its closed position.

30 Novel means is employed for mounting the door in place, so that the door can have sliding movement longitudinally of the car, sliding movement vertically of the car, and swinging movement in a vertical plane. This means includes roller brackets, or castings, 17 and 18, which are mounted for traveling movement on a track 19.

35 The track 19 is provided with a portion 20, which is disposed within the door opening 11 adjacent to the upper end thereof and below the track 14 for the outer door 12, and an outer portion 21, which is disposed exteriorly of the car and beyond and at one side of the door opening. The inner and outer portions 20 and 21 of the track are connected together by an arcuate portion 22 which leads around one side of the door frame. Brackets 23 are employed for holding the track in place.

40 Pivotaly connected with the roller brackets, or castings, 17 and 18, as at 24, are swinging arms, or levers, 25. The lower ends of the arms, or levers, 25 are slidably and rotatably connected with the door A. It will be noted that the lower terminals of the arms, or levers, are provided with transversely extending bearings 26 for supporting a shaft, or pin, 28, the outer terminals of which carry guide rollers 29.

45 These guide rollers 29 are slidably and rotatably received within the guideways 30, bolted or otherwise securely fastened to the door A and adjacent to its upper end. If desired, the guideways 30 can be in the nature of a casting and formed integrally with the straps 16. The exterior upper terminals of the guideways 30 are closed by means of abutment plates, or stops, 31, and the rollers 29 normally rest against said stops so that the door is suspended from said rollers.

50 In use of my improved car door, the door A is slid longitudinally along the track 19 into the door opening. Due to the loose fit of the brackets 17 and 18 on the track the brackets can readily follow the curvature in the track, and, if preferred, additional vertical pivots can be provided to permit the swinging of these roller brackets, or castings.

5 As the door is being slid into the door opening, the same is swung back by means of the levers 25 inwardly of the door frame, and the sliding movement is continued until the right-hand edge of the door (referring to Figure 1) moves past the door opening.

10 After the door has been swung entirely within the door opening, the door can be slid slightly to the left so as to position the left-hand side of the door over the door frame, after which the door is swung outwardly into tight contact with the door frame.

15 Obviously, by raising the door vertically on the rollers 29, movement of the door into the door opening is permitted, and after the door is in position the same is slid downwardly so that tight contact of the door with the floor of the car is insured.

20 Any desired means can be provided for clamping the door tightly in place, and it is also apparent that the weight of the grain against the door will tend to hold the same in position. By way of example, I have shown clamping arms 32 pivotally connected to brackets 33 carried by the door A adjacent to its vertical edges. The brackets 33, if desired, can be swivelly mounted on the door so as to facilitate the position of the door against the door frame.

25 After the door is in proper position, the clamping arms 32 are swung over the outer face of the door frame and are brought into gripping contact with the door frame by the use of suitable wedges, or adjusting screws, 34.

30 Obviously, after the door is in position, the shoveling or spouting of the grain into the car can be continued above the upper edge of the door A. When the car is filled to the desired level, the outer door 12 is slid to its closed position, and this door can be sealed and locked.

35 To effect the easy opening of the door, a slide plate 35 can be carried by the lower end of the door A, and this slide plate normally closes an opening 36 formed in said door. The slide plate 35 is carried by a guide frame 31, which also forms a housing for the upper part of the slide plate so as to prevent the packing of grain thereabout.

40 When the slide plate 35 is raised the release of grain in back of the door can be effected, after which the door can be readily swung to its open position exteriorly of the car.

45 Obviously, the position of the door A is such that the door 12 can be freely used and, if desired, the inner face of the door 12, or jam, can be cut away to compensate for the arcuate connecting portion 22 of the track 19.

50 The door A is so constructed and is associated with the car in such a manner that the same does not take up any unnecessary room, either in its open or closed position, and the door can be made to fit any portion of the opening desired, or changed to fit any opening.

55 From the foregoing description it can be seen that I have provided a novel grain door of exceptionally simple and durable character, which will be economical in use and which will effectively prevent the loss of grain or other loose material.

60 Changes in details may be made without departing from the spirit or the scope of my invention, but what I claim as new is:—

65 1. In a device of the class described, a body having an opening, a door for said opening, a track secured to the body having a portion extending through the door opening and portions

arranged exteriorly and interiorly of the door opening, and means connecting the door with the track for sliding movement in a vertical and horizontal plane through the door opening and swing-
5 ing movement in vertical planes toward and away from the inner faces of the walls of the opening for contact therewith.

2. In a device of the class described, a body having an opening, a door for closing said opening, a guide-track for supporting said door having a portion extending through the opening and portions disposed exteriorly and interiorly of the opening, brackets slidably mounted on the track, arms pivotally connected to the brackets, and
10 means slidably and pivotally connecting the arms to the door, whereby the door can move through the door opening and into contact with the inner faces of the walls of the opening.

3. The combination with a grain car having a door opening and a grain door for closing said opening, of means for associating the door with the car including a track having a portion extending through the door opening and portions extending exteriorly and interiorly of the door opening, brackets slidably mounted on the track, and means pivotally and slidably connecting the door with the brackets, whereby the door can move through the door opening and into contact with the inner faces of the walls of the opening.
25

4. The combination with a railroad car having a door opening, an outer sliding door for closing the opening, and an inner grain door for said opening, of means for supporting the grain door, said grain door being of a greater length than
30 the width of the door opening, a suspension track secured to the car having an inner portion

extending into the door opening and an outer portion extending exteriorly of the door opening, brackets slidably mounted on the track, arms pivotally mounted to the brackets, means slidably and pivotally mounting the lower ends of the arms to the inner door, and clamps carried by
5 said inner door for engaging the walls of the door opening.

5. The combination with a railroad grain car having a door opening and a grain door for effecting the closure of said opening, of means for supporting said door including a horizontally disposed guide-track having an inner portion extending into the opening and an outer portion disposed exteriorly of the car at one side of the door opening, brackets slidably mounted on the track, arms pivotally secured to the brackets, pairs of vertically disposed guide-tracks carried by the door, and rollers carried by the outer ends of the arms slidably and rotatably mounted
10 15 20 within said pairs of guide-tracks.

6. The combination with a railroad car having a door opening, an outer sliding door for closing the opening, and an inner grain door for said opening, means for supporting the grain door, said grain door being of a greater length than the width of the door opening, a suspension track secured to the car having an inner portion extending into the door opening, and an outer portion extending exteriorly of the door opening, brackets slidably mounted on the track, arms pivotally mounted to the brackets, and means slidably and pivotally mounting the lower ends of the arms to the inner door.
